UNITED STATES PATENT OFFICE.

EDWARD T. MITCHELL, OF LISCO, NEBRASKA.

WRENCH.

Application filed June 22, 1925. Serial No. 38,730.

To all whom it may concern:

Be it known that I, EDWARD T. MITCHELL, a citizen of the United States, residing at 5 Lisco, in the county of Garden and State of Nebraska, have invented certain new and useful Improvements in Wrenches, of which the following is a specification.

This invention relates to wrenches, and more particularly to that class of wrenches 10 having a swinging auxiliary handle to aid in gripping the stock.

The principal object of the invention is to provide a device of this character which has relatively few parts and can easily be 15 assembled and adjusted for efficient operation.

Another object of the invention is to provide means to keep the jaws parallel to each other.

20 Other objects will appear as the disclosure progresses. The drawings are intended merely to indicate a possible embodiment of the invention. It is obvious that the actual needs of manufacture may necessitate certain mechanical changes. It is therefore not intended to limit the invention to the embodiment illustrated, but rather to define such limits in the appended claims.

30 For a more detailed understanding of the invention attention is now called to the drawings in which a preferred embodiment is shown illustrated. In these drawings like parts are designated by like reference characters in all the views.

Fig. 1 is a side view, partly in section, of the wrench;

Fig. 2 is a section substantially on line 2—2 of Fig. 1;

40 Fig. 3 is an elevation of the fork;

Fig. 4 is a top view thereof;

Fig. 5 is a view of the transverse arm;

Fig. 6 is a top view thereof;

Fig. 7 is a section on line 7—7 of Fig. 1;

45 Fig. 8 is a view of the threaded sleeve; and

Fig. 9 is a perspective view of the spring.

Referring now to the drawings in detail in which like reference characters denote 50 like parts throughout the specification, numeral 1 designates a shank, 2 the upper jaw integral with the said shank and having teeth on its bottom or working face, 3 the handle, and 4 a U-shaped transverse bar integral with the said handle.

55 Fitting around the shank 1 is a forked

sleeve 5 having pivoting points 6 on which the U-shaped transverse bar 4 having a notch 4^a is adapted to pivot. The shank 1 is threaded on two sides as at 7 and engages the thread of a sleeve 8 having a slot 9 on the outside.

The transverse bar 4 as shown in Figs. 5 and 6 is U-shaped and has a crescent-shaped cutout 10 which co-operates with 65 screws 11. The lower jaw 12 is adapted to fit in the recess 13 of the bar 4 and is held in place by the screw 14.

This device is composed of relatively few parts and can easily be assembled. The 70 downward pressure of the lower jaw is distributed to the forked sleeve 5 and thence to the threaded sleeve 8. For adjustment the sleeve 8 is revolved and the forked sleeve 5 will move either up or down 75 depending on the direction of rotation.

The U-shaped bar 4 is connected to the fork 5 by the screws 11. Any motion of the fork will therefore be transmitted to the bar 4 and thence to the lower jaw. The 80 springs 15 will normally keep the jaws parallel to each other.

For assembling, the fork is placed on the shank 1 and the threaded sleeve 8 is then screwed in place and fastened to the fork 85 by the screws 16. Then the U-shaped bar is passed over the upper jaw 2 and placed in position on the pivoting points 6 and the screws 11 are then inserted. This will allow 90 rocking motion of the bar 4 and still prevent same from falling out of its place. And last, the lower jaw 12 is inserted.

It will thus be seen that I have devised a simple and efficient wrench having relatively few parts and easy to operate.

95 What I desire to secure by United States Letters Patent is:

1. In a device of the class described, in combination, a shank, an upper jaw integral with the said shank having teeth at the bottom, a forked sleeve adapted to move on the said shank, a transverse bar having a handle, the said transverse bar movably fastened to the said forked sleeve, springs for normally keeping the said transverse bar at right angles to said shank, a lower jaw fitting in the forked portion of the said transverse bar, and a threaded sleeve 100 engaging said shank for moving the said forked sleeve on the said shank.

105 2. In a device of the class described, in combination, a shank, an upper jaw integral

with the said shank having teeth at the bottom; a forked sleeve adapted to move on the said shank having pivoting points, a U-shaped transverse bar having a handle adapted to swing on the said pivoting points, means for preventing the said transverse bar from coming out of contact with the said pivoting points; a pair of springs for normally keeping the said transverse bar at right angles to the said shank, a replaceable lower jaw, a threaded sleeve

engaging the said shank, a groove in the said threaded sleeve, and pins adapted to hold the said threaded sleeve and said forked sleeve together and allow for rotation of the threaded sleeve in order to adjust the space between the said upper and lower jaws. 15

In testimony whereof I affix my signature.

EDWARD T. MITCHELL.
